DESIGN FOR A PICTURE FRAME HOLDER

Anna Di Bari, New York, N. Y.

Application May 15, 1943, Serial No. 110,216

Term of patent 7 years

To all whom it may concern:

Be it known that I, Anna Di Bari, a citizen of the United States, residing at New York, in the county of Bronx, in the State of New York, have invented a new, original, and ornamental Design for a Picture Frame Holder, of which the following is a specification, reference being had to the accompanying drawing, forming a part thereof.

Fig. 1 is a side elevational view of a picture frame holder, showing my design; Fig. 2 is a rear elevational view of the same, and Fig. 3 is a top plan view of the same. The front face of the picture frame holder is a flat plane surface.

I claim:

The ornamental design for a picture frame holder, as shown and described.

ANNA DI BARI.
